UNITED STATES PATENT OFFICE.

CHARLES E. SCRIBNER, OF JERICHO, VERMONT, ASSIGNOR TO WESTERN ELECTRIC COMPANY, OF NEW YORK, N. Y., A CORPORATION OF ILLINOIS.

TELEGRAPH-TRANSMITTER.

1,075,503.

Specification of Letters Patent.

Patented Oct. 14, 1913.

Continuation of application Serial No. 648,351, filed September 8, 1911. This application filed November 28, 1911. Serial No. 662,843.

To all whom it may concern:

Be it known that I, CHARLES E. SCRIBNER, citizen of the United States, residing at Jericho, in the county of Chittenden and 5 State of Vermont, have invented a certain new and useful Improvement in Telegraph-Transmitters, of which the following is a full, clear, concise, and exact description.

This invention relates to printing tele- 10 graphs, and more particularly to a printing telegraph transmitter in which the impulses used to select characters at the receiving end of the line are transmitted over a line composed of two main line conductors with a 15 ground return.

This application is a continuation of my copending application, Serial No. 648,351, filed September 8, 1911.

The object of this invention is to provide 20 an improved transmitter in which a combination of two direct current impulses is sent to the receiving station over one or both of the main line conductors and in which the duration of the interval between impulses 25 and the duration of the second impulse are automatically determined irrespective of the will of the operator.

To the above end contacts are provided 30 which automatically select means for controlling the first of a pair of current impulses and at the same time operate and select means which control the interval between impulses and determine the character of the second impulse.

35 In the drawings—Figures 1 and 2 combined illustrate a complete transmitting system embodying my invention, and in which so much of the key structure as is necessary to understand the operation thereof is 40 shown in perspective.

The system operates generally in the following manner:—The key is depressed to send a combination of selecting impulses to the main line, and on its upward stroke 45 closes the contacts 89, 92, 93, selecting and establishing a circuit through one of the series of current control relays 150 to 153 inclusive, through a selected one of the predetermined impulse means 154 to 159 inclusive, through the interval relay 160, and to ground. This operation places the battery 103 on the line for a period of time determined by the length of time necessary for the depressed key lever to return to its nor-

mal position; the selected predetermined 55 impulse means or selector is energized and locked up; the interval relay is energized attracting its armature. At the cessation of the first impulse the selected current control relay is deenergized, removing battery 103 60 from the line. The interval relay is also deenergized and its armature returns to normal. The length of time necessary for the armature of the interval relay to return to normal is the measure of the time between 65 successive impulses. When the armature of this interval relay reaches its retracted position a circuit through a current control relay selected by the locked up predetermined 70 impulse means is closed, this circuit passing 70 through a second impulse relay 161. The battery 103 is thus placed to line a second time, the duration of this second impulse being measured by the time necessary for the second impulse relay to attract its armature, at which time the locking circuit through the selected predetermined impulse 75 means is broken and all parts of the device return to normal.

The two keys shown in detail in Fig. 1 are 80 designated by the numerals 33 and 35. The remaining keys are identical in structure with the keys 33 and 35, and it is considered unnecessary to designate any of the remaining keys except the key 52 used for transmitting the selecting impulses for the letter 85 "O," and the keys 41, 42 and 66 which are used for transmitting the impulses for resetting and restoring the mechanism at the receiving end or for providing a space between words or letters.

The key by which the letter "A" is sent is designated by the numeral 33, and a description of this key will be sufficient for the others. The key 33 is pivoted on a shaft 71 95 and is capable of vertical movement, being guided in such movement by a slot in the front plate 72. The key is held in its normal position by the spring 95. Immediately beneath the key is a transverse rod 73 having rearward extensions 74, one of which is shown journaled at 75 on the pedestal 76, and held in its normal position by the spring 77. At the outer extension of the rod 73 is a pin 79 working in a slot 80 of a plate 81, 100 which plate is journaled on the rod 82. On the outwardly extending arm 83 of the plate 81 is a hollow plunger 84 which moves down

upon the rod 85. Slidably mounted on the rod 85 and positioned between the arm 83 and the lower extension of the plate 81 is an insulating member 87 carried by said plate 81 and held in its upward position by means of the depression 88 formed on the outer end of the contact springs 89, which contact springs are fastened to but insulated from the pedestal 90.

10 91 designates a conductor which may be connected to ground through the contacts 89. Each of the keys controls a pair of contact springs 92 and 93 through the medium of an insulating member 94.

15 Conductors or busbars 1 to 6 inclusive, 10, 20, 30, 40, 50 and 60 are provided, to which the various contacts 92 and 93 may be conveniently connected by conductors 96 and 97 in accordance with the different 20 combinations of impulses to be transmitted. A series of current control relays 150 to 153 inclusive, each having two energizing coils, is provided for controlling the application of the current source 103 to the main 25 line conductors L^1 and L^2 . The energizing coils are connected to the conductors 10, 20, 30, 40, 50 and 60 in such a way that they may be energized by current from battery 98, either singly or in any predetermined 30 group in accordance with the combination of impulses to be transmitted.

Included in the circuit of the one or a group of the current control relays 150 to 153 inclusive selected by a key is one of a 35 series of predetermined impulse relays 154 to 159 inclusive, which relays are used to select a predetermined one or group of the current control relays 150 to 153 inclusive to send the second impulse of a combination 40 of impulses. The energizing coils of these predetermined impulse relays are connected to conductors 1 to 6 inclusive. These predetermined impulse relays are also provided with locking windings which enable the selected relays to remain in operated condition after the cessation of the first impulse 45 of a combination. They also determine through their armatures which one or group of the series of current control relays 50 will be utilized to send the second impulse of the combination.

55 Numeral 160 designates an interval relay which is energized in series with the selected one or group of current control relays and the selected predetermined impulse relay. This relay is of the slow release type and is provided for determining the duration of the interval between successive impulses. The time taken for this relay to become 60 fully deenergized and thus permit its armature to fall to retracted position may be exceedingly short, but is nevertheless of definite and approximately constant duration and determines absolutely the time elapsing 65 between successive impulses. A second im-

pulse relay 161 is also provided and controls the duration of the second impulse to be transmitted to the main line conductors by completing a shunt circuit around the locking circuit of the selected one of the 70 predetermined impulse relays. This relay is made slow-acting by having the resistance 99 in parallel with its energizing winding, and the time necessary for the relay to become fully energized and attract its armature is of definite duration. As in the case of the interval relay above referred to, this time may be exceedingly short but is nevertheless of definite duration and determines absolutely the length of the second impulse. 75 80

The character of the impulses which result from the depression of any of the keys shown may be varied as necessary to produce the desired result at the receiving mechanism situated at the distant end of the line. 85 That is to say the first impulse may be positive battery impressed on either of the main line conductors L^1 or L^2 ; it may be negative battery impressed on either line L^1 or line L^2 , or it may be positive battery impressed on 90 L^1 and L^2 simultaneously. The second impulse likewise may have any of the characteristics of the first impulse. In the preferred form of the invention, however, the first impulse of a combination will never be 95 negative battery impressed upon both the conductors L^1 and L^2 simultaneously, as this form of impulse when not preceded by some other form of impulse and the usual time interval is assigned to and used exclusively for the purpose of producing upon 100 the printing mechanism a space or spaces between succeeding characters. 100

If it is desired to send the letter "A" the key corresponding to this letter is depressed, 105 which depression causes an outward movement of the upper extension of the key 33, making contact between the springs 92 and 93. At the same time the rod 73 is depressed and the pin 79 working in the slot 80 of the plate 81 carries said plate downward moving the plunger 84 into contact with the insulating member 87, forcing said member out from engagement with the springs 89. Springs 89, however, do not contact with 110 each other at this time as the plunger 84 has taken the place of the member 87. Upon the upward movement of the plate 81 the plunger 84 is withdrawn from the springs 89 and these two springs contact 115 with each other for a period of time determined by the time necessary for the plate 81 to rise to its normal position, each time the member 87 is forced between and separates the springs 89. 120

125 When the springs 89 contact with each other a circuit is closed which may be traced from battery 98, lower winding of current control relay 151, conductor or busbar conductor 96, contacts 92, 93, conductor 97 130

conductor or busbar 3, energizing winding of the predetermined impulse relay 156, interval relay 160, conductor 91, contacts 89, to ground. This circuit causes the energization of the current control relay 151, the predetermined impulse relay 156 and the interval relay 160. Current control relay 151 places positive battery on the line L^2 which will remain on line L^2 until the depressed key lever returns to its normal position. Energization of the predetermined impulse relay 156 closes a locking circuit for itself from battery 100. The interval relay 160 attracts its armature which remains attracted until the cessation of the first impulse when it is again moved to its retracted position. The time necessary for the armature to return to its retracted position determines the interval between successive impulses as stated above. When the armature reaches its back contact a circuit is closed from battery 98, through lower winding of current control relay 151, upper armature of the predetermined impulse relay 156, armature of the interval relay 160, through the energizing winding of the second impulse relay 161 and the resistance 99 in parallel to ground. Positive battery is again put to line L^2 from the current source 103 which will continue until the relatively slow-acting relay 161 has fully attracted its armature. When this occurs a shunt is placed around the locking circuit of the predetermined impulse relay 156, thereby breaking the energizing circuit for the current control relay 151 at the upper armature of the predetermined impulse relay, and the second impulse of the combination of impulses ceases.

In the case assumed the operation of the key appropriate to the letter "A" sends two positive impulses over the same line conductor, such impulses being separated by an interval of no current. The operation of the key for the letter "O," however, which will be next described, sends a positive impulse over L^1 and L^2 simultaneously for the first impulse, then an interval of no current, after which the second impulse is sent which consists of negative current sent over L^1 . If the key controlling the impulses for sending the letter "O" is depressed plunger 84 displaces the member 87 from between the contact springs 89, and on the upward stroke of this key the springs 89 close a circuit which may be traced from battery 98 through the lower energizing winding of current control relay 150, and the upper energizing winding of current control relay 151 in parallel, conductor or busbar 50, conductor 96, contact springs 92 and 93 of the appropriate key, conductor 97, conductor or busbar 2, energizing winding of the predetermined impulse relay 157, interval relay 160, conductor 91, contact springs 89 to

ground. The energization of the current control relays 150 and 151 places positive battery 103 to the main line conductors L^1 and L^2 simultaneously. As before, the duration of this impulse is determined by the key lever reaching its normal or upward position. Predetermined impulse relay 157 is energized and locked up. The interval relay 160 which was energized by the circuit above traced allows its armature to retract thus determining, as in the previous case, the duration of the interval between impulses. When the armature of interval relay 160 reaches its back contact a circuit is closed from battery 98, upper energizing winding of current control relay 152, the upper armature of predetermined impulse relay 157, armature of interval relay 160, through the second impulse relay 161 and the resistance 99 in parallel to ground. The closure of this circuit energizes the current control relay 152 and places negative battery from the current source 103 to the main line conductor L^1 . The duration of this impulse is, as above described for the letter "A," determined by the time necessary for the second interval relay to fully attract its armature, which attraction places a shunt around the locking circuit for the predetermined impulse relay 157, deenergizing said switch and sending all parts of the device back to normal position.

In order to provide means for printing the alternate characters indicated on the keys, a shift key is provided which when depressed will so change the operation of the receiving mechanism that as long as the key is maintained depressed nothing but such alternate characters will be printed at the receiving end. This key, shown in detail on Fig. 2 and designated by the numeral 104, is pivoted on a shaft 105, and held in normal position by the spring 106. This shift key also works in a slot in the front plate 72 as do the rest of the keys of the device. This key carries two bell crank levers 107 and 108 pivoted at 109 and 110 respectively, and held in normal position by their springs 111 and 112, respectively. The shift key springs, designated by the numeral 43, are composed of movable plates 113 and 114 spaced apart by means of the insulating rod 115. These two plates contact respectively with stationary plates 116 and 117. The plate 113 carries a cam surface 118 which contacts with an insulating point 119 projecting from the upper arm of the bell crank lever 107. The downward movement of the key 104 will cause the pin 119 to ride over the cam surface 118, forcing both the plates 113 and 114 rearwardly into contact respectively with the plates 116 and 117. When the pin 119 has reached its lower position it has passed below the point 120 E80

on plate 113 allowing springs 113 and 114 to move out of contact with springs 116 and 117, respectively. On the upward movement of the key, pin 119 rides on the rear face of the cam 118, being forced to the rear thereby, and when the pin 119 reaches the top of the cam it is pulled into its normal position against the stop 170 by the spring 111. The shift key is shown slightly 10 depressed to illustrate clearly the relation of the pins 119 and 127 with respect to the cam surfaces 118 and 126, respectively.

The back shift key springs, designated by the numeral 44, are composed of movable 15 contact plates 121 and 122, spaced apart by means of the insulating rod 125, and contacting respectively with stationary plates 123 and 124. The plate 121 carries a cam surface 126 with which the insulating pin 20 127, projecting from the upper arm of the bell crank lever 108, contacts on the up stroke of the switch key 104. On the downward movement of the key 104 pin 127 rides on the rear face of the cam 126, being forced 25 rearwardly thereby and when the pin reaches the lowest point of the cam it is pulled into its normal position against the stop 171 by the spring 112. On the upward movement 30 of the key 104, pin 127 rides on the cam surface 126 forcing plates 121 and 122 into contact, respectively, with plates 123 and 124, and when the pin 127 reaches the top of the cam, plates 121 and 122 spring into their normal position out of contact with plates 123 and 124, respectively. The depression of the shift key causes a 35 combination of impulses to be sent over the line conductors to operate the shifting mechanism at the receiving station, and as long 40 as this key is held depressed the alternate characters only, shown on the keys at the transmitting end, are printed at the receiving end. On the up stroke of this shift key another combination of impulses is sent 45 to the receiving end which operates mechanism to restore the character device to its normal position.

Reset and paper lift key 41, reset key 42, spacing key 66, and all the other character 50 keys shown, operate to send appropriate combinations of impulses to line to actuate at the receiving end the reset and paper lift mechanism, the reset mechanism, and the spacing mechanism, respectively, but as they 55 operate in precisely the same manner as the keys heretofore described, a detailed description of their operation is unnecessary.

From the above description it will be seen 60 that my invention involves an improved and novel system and apparatus for transmitting character selecting impulses, positive or negative, or any combination thereof, and in which the second impulse is of definite duration, the interval between impulses being 65 also of definite duration, the duration of the

second impulse and the duration of the interval between impulses being determined independently of the will of the operator. In every case a manually operated key is depressed, which, after being released by 70 the operator, closes a circuit, energizing one or a group of a series of current control relays, and predetermined impulse relays. Upon the release of the manually operated key the circuit closed thereby places electrical apparatus in condition to determine 75 the interval of time between successive impulses, and also transfers the control of the impulse sending battery from the current control relay first energized, and either gives 80 the control back to this same relay or may transfer it to one or a combination of the current control relays depending on the character of the impulse to be sent. The duration of the second impulse is therefore 85 under the control of electromagnetic apparatus.

I claim:

1. In an apparatus of the class described, a series of switches, key controlled means 90 for momentarily actuating a predetermined one of said series of switches, a selector also actuated by the key controlled means for actuating a second predetermined one of said series of switches.

2. In an apparatus of the class described, a series of switches, means for automatically operating selected ones of said series of switches in predetermined succession in response to a single initial act, said means including a key for momentarily actuating a predetermined one of said series of switches, an interval determining device also controlled by said key, and a selector operated by the return of the interval determining 105 device to normal to actuate a second predetermined one of said series of switches.

3. In an electrical impulse transmitter, the combination with a series of switches, of means for successively operating predetermined groups of said series of switches, said means including a key operated device for momentarily actuating a predetermined group of said series of switches for sending an electrical impulse to line, an interval 115 determining device controlled simultaneously with the group of switches and operating, on its return to normal, a second group of the said series of switches, whereby a second electrical impulse is sent to line, and 120 the duration of the interval between impulses is automatically determined.

4. In an electrical impulse transmitter for automatically sending a succession of impulses to line as the result of a single contact 125 operating action of a key, a circuit including an interval relay, a current control relay and a key operated interval contact, the operation of the interval contact momentarily energizing the interval relay and cur- 130

rent control relay, whereby an electrical impulse is sent to line, the deenergization of said interval relay completing a circuit to again energize said current control relay 5 whereby a second electrical impulse is sent to line.

5. In an electrical impulse transmitter, a key, a current-control relay, an interval relay, means controlled by said key for momentarily energizing both of said relays, a reenergizing circuit for said current control relay arranged to be completed through a back contact of said interval relay upon the recovery of the latter from its momentary 10 excitation, whereby said current control relay is automatically operated a second time.

6. In an electrical impulse transmitter, a source of current, a relay to intermittently connect said source of current to line, a circuit 15 for said relay arranged to be closed momentarily by a key operated contact, a slow acting relay also in said circuit, and a second energizing circuit for the first relay independent of the key operated contact 20 completed at the back contact of said slow acting relay, whereby the first relay is automatically again excited as the slow acting relay recovers upon the opening of the key 25 operated contact.

30 7. In an electrical impulse transmitter, the combination with a main line, of a local circuit including a key controlled contact, a current control relay, a predetermined impulse relay, and an interval relay; a source 35 of current momentarily connected to said main line upon the actuation of the key controlled contact; a circuit including the armatures of said interval and predetermined impulse relays, and said current control relay for automatically exciting said current 40 control relay, the energization of the current control relay again connecting said source of current to the main line.

8. In an electrical impulse transmitter, a 45 key, a pair of impulse contacts controlled by said key, a circuit including said pair of contacts, an interval relay, a predetermined impulse relay, and a current control relay; a main line, a source of current controlled by 50 the armature of said current control relay to send an impulse over the main line during the closure of said impulse contacts; a locking circuit for said predetermined impulse relay holding the relay energized irrespective of the condition of the impulse 55 contacts; a second circuit closed upon the de-energization of said interval relay and including the armature of said predetermined impulse relay, and the current control relay, closure of this last named circuit energizing the current control relay and again connecting said source of current to said line.

9. In an electrical impulse transmitter, a 60 key, a pair of impulse contacts controlled by said key, a circuit including said pair of

contacts, an interval relay, a predetermined impulse relay, and a current control relay; a main line, a source of current controlled by the armature of said current control relay to send an impulse over the main line 70 during the closure of said impulse contacts; a locking circuit for said predetermined impulse relay holding the relay energized irrespective of the condition of the impulse contacts; a second circuit closed upon the de-energization of said interval relay and including a second impulse relay, armature of said predetermined impulse relay, and the current control relay, closure of this last named circuit energizing the current control relay 75 and again connecting said source of current to said line, and a shunt circuit for the said locking circuit closed at the front contact of the second impulse relay when the same is energized, whereby the duration of the 80 second impulse is determined.

10. In a transmitter of the character described, the combination of a main line, a source of electricity, a series of switches for applying varying impulses to said line in 90 succession, means for selecting pairs of said switches including a local circuit, a branch circuit including contacts controlled by a relay in the local circuit to determine the second switch to be operated; and means for 95 closing said local circuit through the contact operated by said relay.

11. In a transmitter of the character described, the combination of a main line, a source of electricity, a series of electromagnetic switches for applying varying impulses to said line in succession, means for selecting a pair of said switches including a local circuit, an interval relay, a branch circuit having an electromagnet therein, said 100 branch circuit including contacts controlled by said interval relay, the coil of one of said electromagnetic switches, and a contact controlled by an electromagnet in the branch circuit; and manual means for closing said 110 local circuit through said interval relay and closing the contact operated by said electromagnet.

12. In a transmitter of the class described, the combination of a main line, a source of 115 electricity, a series of electromagnetic switches for applying varying impulses to said line in succession, means for selecting a pair of said switches including a local circuit, an interval relay, a branch circuit including contacts controlled by said interval relay, the coil of one of said electromagnetic switches and a contact controlled by a relay in a branch circuit to determine the second electromagnetic switch to be energized; 120 and means for closing said local circuit through said interval relay and the contact operated by said relay.

13. In a device for transmitting electrical 125 impulses, the combination of a main line 130

comprising two conductors and a return lead, a source of current, a local circuit including a plurality of means for controlling the connection of said source of current intermittently to said main line during a predetermined interval of time, and means for automatically providing a constant interval between connections.

14. In an electrical impulse transmitter for transmitting signals composed of but two impulses, the combination of two main line conductors, a source of current adapted to be connected to said main line conductors, a plurality of current controlling means, means for selecting any combination of such means, a predetermined time impulse means controlled by said selecting means and defining the duration of an impulse sent over a line conductor, a circuit including a time interval relay and means for predetermining any second combination of said current controlling means, and a second circuit including means for operating the current controlling means and for determining the duration 25 of the second impulse.

15. In an electrical impulse transmitter, the combination with a main line comprising two conductors and a return lead, of a source of current adapted to send positive current simultaneously over both main line conductors, a local circuit including a plurality of means for connecting said source of positive current to said main line conductors during a predetermined interval of time, said local circuit also including means for determining the duration of a second impulse, means for determining the duration of the pause elapsing between the two impulses, and means for predetermining a plurality of the current controlling means for sending the second positive impulse simultaneously over the main line conductors.

16. In an electrical impulse transmitter, a main line, a source of current adapted to be intermittently connected thereto, in combination with a series of current control relays for intermittently connecting said source of current to said line, a key operated impulse contact to select predetermined groups of said series of current control relays, and means for automatically providing a constant interval between connections.

17. In an electrical impulse transmitter, the combination with a main line comprising two conductors and a return lead, of a series of current control relays, a series of predetermined impulse relays, a local circuit including a pair of contacts, a pair of impulse contacts, a group of said series of current control relays, a predetermined impulse relay, and a time interval relay; a locking circuit for said predetermined impulse relay; a source of current adapted to apply an impulse to the main line conduc-

tors upon energization of said group of current control relays, the duration of such impulse being determined by said pair of impulse contacts; and a second circuit established upon the deenergization of said interval relay a definite period after the opening of said first circuit, said second circuit including a second impulse relay, contacts of the said predetermined impulse relay and a group of current control relays, the energization of such group of current control relays 75 applying a second impulse from said source of current to said line conductors and the energization of said second impulse relay after a definite interval restoring said current control and predetermined impulse 80 relay to normal.

18. In a printing telegraph transmitter, the combination with a local circuit including a current control relay, bridging contacts, a predetermined impulse relay, a time 85 interval relay, and a pair of impulse contacts; of key operated means to momentarily close said bridging contacts and said pair of impulse contacts; a locking circuit for said predetermined impulse relay holding the 90 predetermined impulse relay energized irrespective of the condition of either the bridging contacts or the impulse contacts; a second circuit closed upon the deenergization of the time interval relay and including a second impulse relay, an armature of the 95 time interval relay, an armature of the predetermined impulse relay and the current control relay; a main line; and a source of current adapted to be connected to and disconnected from said main line upon the energization and deenergization of said current control relay, the duration of an impulse transmitted to the main line from the source of current, and the duration of the interval 100 elapsing between impulses being determined 105 independently of the will of the operator.

19. In an impulse transmitter a plurality of current control relays, a plurality of predetermined impulse means greater in number than the number of current control relays, means for selectively operating one or a group of the plurality of current control relays and one of the predetermined impulse 110 means to transmit an impulse, said predetermined impulse means closing a point in a circuit through one or a group of the current control relays, and means for completing the circuit to send a second impulse.

20. In an impulse transmitter a plurality of current control relays, a plurality of predetermined impulse relays greater in number than the number of current control relays, means for selectively operating one or a plurality of current control relays and one 125 of the predetermined impulse relays to transmit an impulse, said predetermined impulse relay closing a point in a circuit

through one of the current control relays, and means for completing the circuit to send a second impulse.

21. In an impulse transmitter for transmitting a plurality of characteristic impulses, the combination of a series of predetermined impulse relays equal in number to the number of characteristic impulses to be transmitted, a source of current, current control relays less in number than the number of impulses, key operated means controlling the circuit through one or a group of the current control relays and a predetermined impulse relay, and a second circuit through one or a group of the current control relays under the control of the energized predetermined impulse relay.

22. In an impulse transmitter a plurality of current control relays, a plurality of predetermined impulse relays greater in number than the number of current control relays, means for selectively operating one or a group of the plurality of current control relays and one of the predetermined impulse relays to transmit an impulse, said predetermined impulse relay closing a point in a circuit through one of a group of the current control relays, means for completing the circuit to send a second impulse, and means co-

operating with said predetermined impulse relays to determine the duration of the second impulse.

23. In a printing telegraph transmitter, the combination of two main line conductors, a source of current adapted to be connected to either or both of the main line conductors, a plurality of means for controlling the application of said source of current to said line conductors, means for selectively operating one of said plurality of current control means to apply said source of current to the line conductors for a predetermined interval of time, predetermined impulse means greater in number than the said current control means also operated thereby, said predetermined impulse means shifting the control of said source of current to another one or group of the plurality of current control means to apply said source of current to the line conductors a second time.

In witness whereof, I, hereunto subscribe my name this 21st day of November A. D., 1911.

CHARLES E. SCRIBNER.
